ATTORNEY

UNITED STATES PATENT OFFICE

WILLIAM JOHN SAMUEL, OF CHATHAM, ENGLAND

AUTOMATIC THEFT PREVENTION DEVICE

Application filed April 3, 1931, Serial No. 527,552, and in Great Britain April 12, 1930.

Of late there has been an increase in the number of robberies from shop windows or show cases even during the day time. A window is broken by means of a heavy article, and a tray of jewels, for example grabbed by the thief.

The present invention aims at preventing the thief from seizing the goods after he has broken the window, and it has the advantages that it does not obstruct the sight of the goods when it is in its inoperative position, and that it works swiftly and is not dependent upon the functioning of an electric circuit, which may get out of order.

With this and other objects in view I provide according to the present invention, for the protection of goods in a window, an intercepting device which rests upon a bracket or platform hinged at one end to a carrying member and held up at the other end by struts resting at their lower ends, by the aid of a roller or equivalent, upon a member which is maintained in its holding position by a piece extending to the window or like pane, so that when the latter is jarred or broken, the ends of the struts are deprived of their support and consequently, the said intercepting device falls down.

The said intercepting device may be in the form of a grille or portcullis, or a shutter, partition, screen or blind (preferably a roller blind composed of rigid laths) which for convenience will hereinafter be termed a blind.

One constructional embodiment of my invention as applied to a shop window will now be described by way of example, with the aid of the accompanying drawing illustrating the same, in which Figure 1 is a side elevation and Figure 2 a rear elevation. A portion of the window is also shown.

At the sides of the window vertical channels of any convenient form are provided in which the blind can slide up and down and be prevented from being pushed inwards or outwards. The blind is composed of horizontal laths A hinged together in any suitable manner and suspended by a roller or in any other way so that it can rapidly descend by gravity when desired. To facilitate the

descent, a heavy bar B is attached to the bottom of the blind. In its upper position, the laths A are concealed from view (for instance by a valance) likewise the means for supporting the blind, which is conveniently in the form of a bracket C carried upon a vertical piece D, fastened to the top member of the window frame or to any other means of support E at some height above and within or slightly behind the plane of the window pane F. The bracket C is hinged horizontally to the vertical piece D and forms a platform extending backwards (i. e. into the shop), when held horizontal or thereabouts by a pair of inclined parallel hinged struts G. The latter extend downwards and are connected together at their lower ends by a horizontal cross-rod H carrying a roller J resting normally upon a special support, which becomes displaced by the breaking of the window so causing the platform to fall into a vertical position and no longer give support to the blind which instantly comes crashing down at a great speed.

The support for the struts, in the example under consideration, comprises a wheel or roller K, mounted in a hinged extension L of the vertical piece D, the extension L being suspended from the upper part D by a hinge M allowing it to sway when free to do so. The said upper part D is fastened rigidly at some point high up in the window (such as by screws N connecting it to the support E) and the lower extension L is given a tendency to swing towards the glass F by reason of the pressure of the struts G, which are inclined downwardly towards it, and it is prevented from actually touching the glass by a small spring plunger O or some such equivalent device. The spring plunger O has a head as illustrated, works in a small bracket P, and carries a spring Q between its head and the said bracket. The vibration or shock of a blow upon the glass F is transmitted to the hinged portion L of the vertical piece D, causing it to dislodge the roller J of the cross-rod H from the wheel or roller K, the roller J then rolling off from the wheel or roller K, and the latter may be grooved or flanged on both faces to prevent lateral disengagement.

The suspended hinged extension L of the vertical piece D may also carry buffer springs R, auxiliary to the spring plunger O or the like already mentioned.

- 5 Whilst rollers J and K as described are desirable owing to their anti-friction properties, it is nevertheless possible that suitably shaped smooth surfaces for interengagement might in some cases be substituted. For example, there might be a combination of a roller and an ogee-shaped member so arranged that when the window is given a blow with a brick or other heavy object, the portion of the spring plunger O in contact with the glass F will tremble, which trembling will be transmitted to the ogee support and cause the roller J to roll off the same. This will cause the bracket C to fall smartly, allowing the heavy bar B and the blind A to descend. 15 Thus the thief is prevented from laying his hand upon any of the goods. A switch such as S may be positioned in one of the guide-ways so that an electric alarm bell T worked from a battery U may be rung—also lighting a lamp V—when the blind falls or any other suitable sounding alarm may be substituted. 20

By the suitable adjustment of the length of the struts G carrying the roller K the sensibility of the device can be varied.

- 30 It is to be understood that my invention is not limited to the arrangement above described, but is capable of wide variation, for example, the blind may be of any type, and material, the platform support may be of any shape and formed with any suitably curved surface and the vertical piece D to which the bracket is secured and the part L may be formed in one piece. 35

40 I claim:—

1. In an automatic theft prevention device for use in shop windows, display cabinets and the like of that type including an intercepting screen adapted to fall into position between the window pane and the goods in the display area, the combination of a bracket normally supporting said screen in an elevated position, a carrying member to which one end of said bracket is hinged, means for holding said member high up in permanent position, struts hinged to said bracket so as to be capable of hanging downwards therefrom, and displaceable means for supporting the lower ends of said struts, the displacement of which is occasioned by the jarring or breakage of the window pane. 45

- 50 2. In an automatic theft prevention device for use in shop windows, display cabinets and the like of that type including an intercepting screen adapted to fall into position between the window pane and the goods in the display area, the combination of a bracket normally supporting said screen in an elevated position, a carrying member to which one end of said bracket is hinged, means for holding said member high up in permanent

position, struts hinged to said bracket so as to be capable of hanging downwards therefrom, an extension hingedly suspended from the said carrying member, means for supporting the bottom extremities of said struts upon the said extension, and means between the latter and the window pane for maintaining said extension in its supporting position, so that such position is dependent upon the pane remaining intact. 70

75 3. In an automatic theft prevention device for use in shop windows, display cabinets and the like of that type including an intercepting screen adapted to fall into position between the window pane and the goods in the display area, the combination of a bracket normally supporting said screen in an elevated position, a carrying member to which one end of said bracket is hinged, means for holding said member high up in permanent position, struts hinged to said bracket so as to be capable of hanging downwards therefrom, a rod connecting the lower ends of said struts, an anti-friction element upon said rod, displaceable means upon said extension for supporting said element, and means between the latter and the window pane for maintaining said extension in its supporting position, so that such position is dependent upon the pane remaining intact. 80

85 4. In a theft prevention device of that type including an intercepting screen, the combination of a bracket normally supporting the screen in non-intercepting position, a carrying member holding said bracket hingedly, means for holding said carrying member fixedly, struts hinged to said bracket hinged means for supporting displaceably the lower ends of said struts, and means for keeping said hinged means at such a distance from the window pane which when jarred or broken will no longer support the said struts and cause the bracket with the screen resting upon it to descend and cut off access to the goods by the intending thief. 90

100 5. In a theft prevention device of that type including an intercepting screen, the combination of a bracket normally supporting the screen in non-intercepting position, a carrying member holding said bracket hingedly, means for holding said carrying member fixedly, struts hinged to said bracket, hinged means for supporting displaceably the lower ends of said struts, and a resilient distance piece between the window pane and the lower end of said hinged means. 110

115 6. In an automatic theft prevention device for use in shop windows, display cabinets and the like and of that type including a vertically movable intercepting screen adapted to fall into position between the window pane and the goods in the display area, the combination of a stationary upstanding support, an element hinged to said support intermediate its ends for disposition at right angles 120

thereto to normally hold the screen in non-intercepting position, an extension hinged to the lower end of and depending from said support, struts hinged to and depending from said element, a resilient device normally acting, while the window pane is intact on said extension for forcing the latter in a direction away from the window pane, and means carried by said extension for releasably supporting the struts in upstanding position for maintaining said element in holding position during the normal action of said device.

7. In an automatic theft prevention device for use in shop windows, display cabinets and the like and of that type including a vertically movable intercepting screen adapted to fall into position between the window pane and the goods in the display area, the combination of a stationary upstanding support, an element hinged to said support intermediate its ends for disposition at right angles thereto to normally hold the screen in non-intercepting position, an extension hinged to the lower end of and depending from said support, struts hinged to and depending from said element, a resilient device normally acting, while the window pane is intact on said extension for forcing the latter in a direction away from the window pane, means carried by said extension for releasably supporting the struts in upstanding position for maintaining said element in holding position during the normal action of said device, and resilient distance means carried by and extended from the lower end of said extension.
